UNITED STATES PATENT OFFICE.

CHARLES HENRY ALEXANDER DAVIS, OF SAN RAFAEL, CALIFORNIA.

HOLDING-VISE ATTACHMENT.

1,025,739.

Specification of Letters Patent.

Patented May 7, 1912.

Application filed October 27, 1910. Serial No. 589,503.

To all whom it may concern:

Be it known that I, CHARLES HENRY ALEXANDER DAVIS, a citizen of the United States, residing at San Rafael, in the county of Marin and State of California, have invented new and useful Improvements in Holding-Vise Attachments.

My invention relates to an attachment for holding vises.

10 It consists of a pair of supplemental jaws adapted to fit between the main permanent jaws of the vise, and having the backs or contacting surfaces of said jaws made convex and with suitable supporting flanges. 15 The inner faces of the jaws consist of interlocking lugs with suitable gripping surfaces; the object of the jaws being to enable them to automatically engage tapering or irregular forms without change in the jaws 20 of the main vise.

It also comprises details of construction which will be more fully explained by reference to the accompanying drawings, in which—

25 Figure 1 is a plan view showing the application of my invention to an ordinary vise. Fig. 2 is a side elevation. Fig. 3 is a perspective view of the separated jaws.

These jaws may be applied to any vise 30 having plain, straight jaws such as indicated at A. The jaws 2 may be also made of any suitable material for the purposes for which they are to be used. The vertical back portion 2' of each jaw rests against 35 the corresponding vertical straight face of the vise, and these faces 2 are convexly curved so that if a tapering or irregular article is to be held between the jaws, the closing of the vise will cause these jaws to 40 automatically adjust themselves so as to preserve an even grip upon the whole of the surface, thus a tapering or wedge-shaped article may be held between these jaws which will grip it firmly from end to end.

45 In order to retain the jaws in place, I have shown lips or flanges 3 which project from the top above the convex surfaces, and these lips or flanges resting upon the top of the vise will prevent the supplemental 50 jaws from falling out when the vise is open.

The interior faces of the jaws are made with projecting tongues 4 alternating so that when the jaws are closed together these tongues interlock. The inner surfaces of 55 the tongues may be made concave, as shown at 5, and may also have these concave surfaces corrugated or made to grip with a firm hold. If a large article is placed between these jaws and the vise closed, it will 60 be seen that the curved backs of the jaws will cause them to incline with relation to the article which is being held; thus a tapering rod will be held firmly between the jaws, which, if the article is large, will not 65 interlock at all. If the article is small the teeth will interlock, and they may interlock to such an extent that the smallest wire will be firmly gripped between them. A pair of these jaws may be fitted to any vise 70 and thus render it serviceable for firmly holding tapering or irregular forms without mutilating the faces of the main jaws or making any permanent attachment for 75 the supplemental jaws.

Having thus described my invention, what I claim and desire to secure by Letters Patent is—

1. The combination with a vise having parallel jaws, of a pair of supplemental 80 jaws having horizontally convex backs and overhanging flanges, and vertical, concave, corrugated, and interlocking lugs projecting from the inner faces of said jaws.

2. Supplemental holding jaws, having 85 convex backs adapted to fit between plain vise jaws, lips or flanges projecting from the upper portion to rest upon the tops of the vise jaws, and interlocking lugs forming the inner gripping surfaces of said jaws. 90

3. Independent holding jaws for vises, said jaws having convex backs and overhanging lips to contact with and be supported by the main jaws, and interlocking tongues forming the holding portions of 95 said jaws and having concave, corrugated faces.

CHARLES HENRY ALEXANDER DAVIS.
